UNITED STATES PATENT OFFICE.

FRANK KUSTERLE, OF KENOSHA, WISCONSIN, ASSIGNOR TO SIMMONS COMPANY, OF KENOSHA, WISCONSIN, A CORPORATION OF DELAWARE.

CRIB.

Application filed October 7, 1921. Serial No. 506,096.

My invention relates to improvements in cribs and has particular reference to the means for locking the crib side or gate in elevated position.

5 The principal objects of the invention are to provide a crib having a side gate so arranged that it may be readily unlocked by an adult person, while at the same time, it is so securely held in elevated position that 10 a child cannot unlock same and fall out; to provide an improved arrangement which shall be neat and inconspicuous and shall not interfere in any way with the proper disposition of the bedding; to provide an 15 arrangement of the class described which may be unlocked by a comparatively simple manipulation and which will be practically self-latching when the crib gate is raised into elevated position; to provide a construction which shall be simple and inexpensive 20 to manufacture, and in general to provide an improved and efficient crib construction of the character referred to.

In the drawings which illustrate my invention as applied to a crib made of wood, 25 Fig. 1 is a side elevation of the crib;

Fig. 2 is a section taken on the line 2—2 of Fig. 1;

Fig. 3 is a section taken on the line 3—3 30 of Fig. 1 but showing the parts in slightly different position, and

Fig. 4 is a section taken on the line 4—4 of Fig. 2.

Referring to the drawings, it will be observed that the main frame of the crib includes a pair of corner posts 10 and 11, between which posts the crib side or gate 12 may be moved down or up in order to render the interior of the crib more accessible or 40 to prevent the occupant of the crib from falling therefrom. Said side gate 12 comprises a top rail 13 and a bottom rail 14, said rails being connected by a series of vertical filler bars 15 suitably secured at their ends to said 45 rails.

The extremities of the upper rail 13 are equipped with cap members 16 which comprise end plates 17 having lug extensions, as at 18, bent down to enclose the ends of 50 the rail 13 and secured in place by suitable pins or nails 19. The bottom rail 14 has its ends equipped with similar cap members 20, which cap members 20, however, are additionally equipped with locking pins, as indicated at 21. Said locking pins 21 comprise

small rivets, the heads of which are seated upon the ends of the rail 14 and the shanks of which extend through apertures punched in dished portions 22 of the end plates of said caps 20.

60 The horizontally disposed lug parts of the caps 19 and 20 are perforated, as also are the ends of the rails 13 and 14, to admit the vertically extending guide rods 23, upon which the crib side 12 is slidably arranged. 65 Each of said rods 23 comprises a somewhat flexible steel wire or rod, the upper end of which is bent at right angles and inserted through an aperture drilled horizontally in the post 10 or 11, as the case may be. Said 70 bent end portion 24 is rigidly maintained in fixed position by means of a screw 25 which is inserted into the end of said horizontal portion 24. The lower end of each of the guide rods 23 extends through and is 75 supported by a small strap metal bracket 26, said bracket having a vertically disposed part 27 extending along the crib post and rigidly secured thereto in any suitable manner, as by nails or screws 28. Preferably, 80 in order to lessen noise and shock when the crib gate is suddenly released, a rubber washer or bumper 29, perforated to admit the rod 23, is placed upon the upper side of the bracket 26.

85 The interengaging means or members by which the crib gate is maintained in elevated position comprise the pins 21, heretofore referred to, and suitable brackets 30 secured to the sides of the crib posts by suitable 90 screws 31 or other means. Each of said brackets comprises a stamped metal member, the intermediate portion 32 of which is spaced from and extends parallel with the surface of the corner post. Said intermediate 95 portion 32 of the bracket is formed or cut out, as indicated best in Figs. 2 and 4, to provide an opening or passageway 33 for the locking pin 21 and a seat 34 for said locking pin. Preferably, sufficient metal is 100 left in place to provide a horn or hook 35, which is located intermediate the seat 34 and the guideway or passageway 33. Preferably, the passageway under the hook 35 is formed with a curved or cam surface 36 105 which is engaged by the pin 21 as the latter is carried upwardly when elevating the side gate into locked or latched position. In order to prevent interference with the free upward movement of the pin 21, the lower 110

end of the passageway 33 is extended into the bottom leg or horizontally extending part 37 of the bracket 30.

The operation of the device is rendered effective by arranging matters so that the lower ends of the crib side are normally forced in a direction to move the locking pins 21 from the passageway 33 into the seat 34. In the present instance the lower side of the gate is acted on by forces tending to move same outwardly. In the preferred form of the invention said force effective to move the pins in the direction to lock the side gate into position is obtained not with additional springs or other mechanism, but through the agency of the guide rods 23 which are constructed of such material and are of such dimensions that before installation in the crib, they may be slightly bent or bowed outwardly, thereby causing same to function as springs as well as guides.

Under normal conditions, the guide rods 23 assume a position such that the pins 21 in the ends of the bottom rail 14 locate themselves slightly outside of the straight line extending between the top and bottom of the guide rods. In order to latch the gate in elevated position it is merely necessary to elevate the side gate far enough to enable the locking pins 21 to snap beyond the points of the hooks 35, and then to release the gate. The pins 21 will then assume the positions shown in Fig. 2 and the gate will be securely latched in elevated position.

In order to lower the gate the same is lifted by the rod 13 far enough to enable the pin 21 to clear the top of the hook 35, whereupon, upon a slight inward pressure of the knee against the middle of the bottom rail, the rods 23 will be fixed sufficiently to shift the pins 21 into the top portion of the passageway 33 and beyond the points of the hooks 35. The side gate is then permitted to descend, of course maintaining the slight inward pressure on the rail 14 until the pins 21 have dropped below the hooks 35. The gate is then enabled to descend without further manipulation or effort upon the part of the operator.

The described details of construction being merely illustrative of a single phase of my invention, it will be understood that the scope of same should be determined by reference to the appended claims, such claims being construed as broadly as possible consistent with the state of the art.

I claim as my invention:

1. In a crib, the combination of a main frame, a side gate movable up and down in said frame, a resilient guide on which the side gate is movable, and cooperating interengaging means carried respectively by the

frame and guide for maintaining the gate in an elevated position, said means being adapted to engage and disengage against a yielding tension of said guide.

2. In a crib, the combination of a main frame, a side gate movable vertically in said frame, a spring rod affording a guide on which the side gate is vertically movable, and cooperating interengaging members carried respectively by the frame and guide for maintaining the gate in an elevated position, said means being adapted during the interengaging operation to displace an intermediate portion of the spring rod laterally and thereby afford a spring tension to cause said means to interengage.

3. In a crib, the combination of a main frame, a side gate movable vertically in said frame, cooperating interengaging members carried respectively by the frame and by a lower portion of the gate for maintaining the gate in elevated position, and resilient means normally tending to effect horizontal movement of said gate portion in order to maintain said members in interengagement, the arrangement including a flexible guide member constituting said resilient means and upon which said gate portion is slidable.

4. In a crib, the combination of a main frame, a side gate movable vertically in said frame, cooperating interengaging members carried respectively by the frame and by a lower portion of the gate for maintaining the gate in elevated position, and resilient means normally tending to effect horizontal movement of said gate portion in order to maintain said members in interengagement, the arrangement including a flexible guide member constituting said resilient means, and upon which said gate portion is slidable, said interengaging members comprising pins at the lower corners of said gate, and seats for said pins on said frame.

5. In a crib, the combination of a main frame, a resilient guide fixed at its upper and lower ends to the main frame, a crib side movable up and down on the guide, and a stationary latch adapted to be engaged by a fixed part on the crib side for detachably holding the latter in the elevated position, said latch and fixed part being adapted to engage and disengage against a yielding tension of said guide.

6. In a crib, the combination of a main frame, a vertically adjustable crib side, a latch member for holding the crib side in the elevated position, and a guide for the crib side having a laterally yieldable portion intermediate of its ends for resiliently holding the crib side engaged with the latch member.

FRANK KUSTERLE.
